(57) **CLAIM**

The ornamental design for a box, as shown and described.

DESCRIPTION

FIG. 1 is a top plan view of a box in an unassembled form showing my new design;

FIG. 2 is a bottom plan view of the box of FIG. 1;

FIG. 3 is a top view of the box of FIG. 1 in an assembled form and in a closed position;

FIG. 4 is a bottom view of the box of FIG. 3;

FIG. 5 is a top perspective view of the box of FIG. 3;

FIG. 6 is a bottom perspective view of the box of FIG. 3;

FIG. 7 is a top right perspective view of the box of FIG. 1 in an assembled form and in an open position;

FIG. 8 is a top left perspective view of the box of FIG. 1 in an assembled form and in the open position shown in FIG. 7;

FIG. 9 is a top right perspective view of the box of FIG. 1 in an assembled form and in a second open position;

FIG. 10 is a top left perspective view of the box of FIG. 1 in an assembled form and in the open position shown in FIG. 9;

FIG. 11 is a bottom perspective view of the box of FIG. 1 in an assembled form and in a third open position;

FIG. 12 is a bottom perspective view of the box of FIG. 1 in an assembled form and in the open position shown in FIG. 9;

FIG. 13 is a top view of the box of FIG. 1 in an assembled form and in the open position shown in FIG. 9; and,

FIG. 14 is a bottom view of the box of FIG. 1 in an assembled form and in the open position shown in FIG. 9.
